CLAIM

The ornamental design for a lighting fixture with acoustic panels, as shown and described.

DESCRIPTION

FIG. 1 is a front, top perspective view of a lighting fixture with acoustic panels;

FIG. 2 is a front elevation view thereof;

FIG. 3 is a back elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a front, top perspective view showing the acoustic panels removed;

FIG. 9 is front elevation view thereof;

FIG. 10 is a back elevation view thereof;

FIG. 11 is a right elevation view thereof;

FIG. 12 is a left elevation view thereof;

FIG. 13 is a top plan view thereof;

FIG. 14 is a bottom plan view thereof;

FIG. 15 is a front, top perspective view of an alternative embodiment of a lighting fixture with acoustic panels;

FIG. 16 is a front elevation view thereof;

FIG. 17 is a back elevation view thereof;

FIG. 18 is a right elevation view thereof;

FIG. 19 is a left elevation view thereof;

FIG. 20 is a top plan view thereof;

FIG. 21 is a bottom plan view thereof;

FIG. 22 is a front, top perspective view showing the acoustic panels removed;

FIG. 23 is front elevation view thereof;

FIG. 24 is a back elevation view thereof;

FIG. 25 is a right elevation view thereof;

FIG. 26 is a left elevation view thereof;

FIG. 27 is a top plan view thereof; and,

FIG. 28 is a bottom plan view thereof.

The broken lines in the drawings depict portions of the lighting fixture with acoustic panels that form no part of the claimed design.
